United States Patent Office

Des. 222,584
Patented Nov. 9, 1971

222,584

OCULIST'S DESK

David M. Lieberman, 9 Prospect Park W.,
Brooklyn, N.Y. 11215

Filed Aug. 5, 1970, Ser. No. 24,331

Term of patent 14 years

Int. Cl. D24—02; D6—01
U.S. Cl. D16—2

FIG. 1

FIG. 2

FIG. 3

FIG. 4

FIG. 1 is a front perspective view of the oculist's desk showing my new design;

FIG. 2 is a side view thereof;

FIG. 3 is a front perspective view of the oculist's desk of my new design with the lens tray extended; and

FIG. 4 is a side view of FIG. 3.

I claim:

The ornamental design for an oculist's desk, as shown.
